UNITED STATES PATENT OFFICE.

ELMI HUBER, OF INGALLS, INDIANA.

BUTTER-MOLD.

No. 893,501.

Specification of Letters Patent.

Patented July 14, 1908.

Application filed April 7, 1908. Serial No. 425,601.

To all whom it may concern:

Be it known that I, ELMI HUBER, a citizen of the United States, residing at Ingalls, in the county of Madison and State of Indiana, 5 have invented certain new and useful Improvements in Butter-Molds; and I do hereby declare the following to be a full, clear, and exact description of the invention, such as will enable others skilled in the art to which 10 it appertains to make and use the same.

This invention relates to new and useful improvements in butter molds and it has primarily for its object to provide a novel device of this character wherein a multiplicity 15 of prints or blocks may be obtained.

It is also an object of the invention to provide a novel device of this character employing an auxiliary base, whereby the prints or blocks may be readily removed after being 20 molded.

It is also an object of the invention to provide a novel device of this character formed of a plurality of sections hinged one to the other, said hinged sections holding the auxiliary base in applied or operative position.

It is also an object of the invention to provide a novel device of this character which will be simple in construction, efficient and advantageous in practice and comparatively 30 inexpensive to manufacture.

With the above and other objects in view, the invention consists in the details of construction and in the novel arrangement and combination of parts to be hereinafter more 35 particularly referred to.

In describing the invention in detail, reference will be had to the accompanying drawings forming part of this specification, wherein like characters of reference denote corresponding parts in the several views, and in 40 which,

Figure 1 is a detail view in perspective of a mold embodying the invention. Fig. 2 is a view in perspective illustrating a plurality of 45 prints or blocks formed by the mold. Fig. 3 is a view in top plan of the invention with the sides thereof distended. Fig. 4 is a cross sectional view.

In the drawings, 1 denotes the base of the 50 mold having hinged to its longitudinal edges, the side boards 2 and to its transverse edges, the end boards 3. It is to be observed that the end boards 3 and side boards 2 are so hinged to the base board 1 as to bring the 55 lower edges of the side boards and end boards a suitable distance above the base board.

This is done in order to permit an auxiliary board 4 being interposed between the lower edges of the side boards and end boards and the base. By this means, it will be seen that 60 the auxiliary base board is effectually held in position.

The side boards 2 are provided intermediate their length with the alining grooves 5, in which fits the transverse partition board 6. The end boards 3 are provided with a plurality of alining grooves 7, which also aline with a series of grooves 8 in the opposed faces of the partition board 6 and within the grooves 7 and 8 fit end portions of 70 the longitudinally disposed partition boards 9. By this arrangement, it will be seen that provision is made for the forming of a plurality of prints or blocks of butter.

The butter is placed within the molds or 75 compartments of the molds and is compressed therein by any suitable blade. After this operation, and it should be desired to move the blocks or prints, it is only necessary that the plates 6 and 9 be withdrawn and the 80 side boards 2 and end boards 3 thrown back, when the auxiliary base 4 can be lifted and set aside for the prints or blocks to harden or to be stored away. By this arrangement, it will be seen that it will not at any time be 85 necessary for the operator to touch the prints with his hand. This is especially advantageous, when the butter is of such softness as not to permit it to be moved manually. In order to expedite the removal of 90 the plates 6 and 9, each of said plates is provided on its upper or exposed edge with an eye 10, which can be grasped by the fingers or by any suitable implement.

The size of the prints or blocks may be as 95 desired, but it has been found best that in producing a mold of this character, the compartments formed by the plates 5 and 9 be of such size as to produce a block or print weighing one pound.

It might be well to further state that the side boards and end boards are held in operative position by means of the hasps 11 pivoted to the end boards and engaging pins 12 on the ends of the side boards 2. This locking means, however, in its specific details, is not essential, as any other arrangement operated with equal facility may be employed.

I claim:

1. In a mold, the combination of a base, 110 boards hingedly carried by the edges thereof, said boards being so hinged as to have their

- lower edges terminating a distance from the base and an auxiliary base board resting on the base and projecting beneath the lower edges of the hinged boards, when said boards are in an elevated position.
2. In a mold, the combination with a base, boards hingedly carried by the edges thereof, said boards being so hinged as to have their lower edges terminating a distance from the base, an auxiliary base board resting on the base and projecting beneath the lower edges of the hinged boards when said boards are in

an elevated position, said boards having their inner faces grooved and partitions extending across the auxiliary base projecting 15 within the grooves of the boards.

In testimony whereof I have signed my name to this specification in the presence of two subscribing witnesses.

ELMI HUBER.
